UNITED STATES PATENT OFFICE.

THOMAS ROWLAND JORDAN, OF NEW YORK, N. Y., ASSIGNOR TO THE JORDAN GRAVITATION COMPANY, OF NEW YORK.

DESIGN FOR A TUBE FOR CONCENTRATING MINERALS.

SPECIFICATION forming part of Design No. 33,579, dated November 20, 1900.

Application filed July 16, 1900. Serial No. 23,843. Term of patent 14 years.

To all whom it may concern:

Be it known that I, THOMAS ROWLAND JORDAN, a subject of the Queen of Great Britain, residing at No. 325 Amsterdam avenue, New York, in the county of New York and State of New York, have invented and produced a new and original Design for Tubes for the Concentration of Minerals, &c.; and I do declare the following to be a full, clear, and exact description of the same, reference being had to the accompanying drawings, forming a part thereof.

Figure 1 is a view in elevation of a tube for the concentration of minerals, &c., exhibiting my new design. Fig. 2 is a cross-sectional view on line 2 2 of Fig. 1.

As shown in the drawings, the leading or material feature of my design consists of the upper and lower tubular portions A and B

and the reduced portion C connecting the upper and lower portions. Between the reduced portion C and the upper and lower portions the tube is of tapering form, the diameter decreasing gradually from the lower end of the upper portion A to the portion C and increasing gradually from said portion C to the upper end of the lower portion B.

Having described my invention, what I claim as new, and desire to secure by Letters Patent, is—

The design for a tube for the concentration of minerals, &c., as herein shown and described.

THOMAS ROWLAND JORDAN.
